Primary Examiner — John R Yeh(74) *Attorney, Agent, or Firm* — Steven J. Grossman; Grossman Tucker Perreault & Pfeifer(57) **CLAIM**

We claim the ornamental design for a flat mop ejection scaffold, as shown and described.

DESCRIPTION

FIG. 1 is a front, top perspective view showing our invention for a flat mop ejection scaffold;

FIG. 2 is a rear, top, left perspective view thereof;

FIG. 3 is a rear, top perspective view thereof;

FIG. 4 is a top, right side perspective view thereof;

FIG. 5 is a top, rear, left side perspective view thereof;

FIG. 6 is a rear, top perspective view thereof; and,

FIG. 7 is a bottom, front perspective view thereof.
